Application June 30, 1943, Serial No. 492,976

7 Claims. (Cl. 235—61)

This invention relates to new and useful improvements in an integrating means, and has more particular reference to an integrating mechanism adapted to continuously integrate the product of two variables and to register the result on a counter. One use for the integrating means would be to totalize continuously the weight of material carried by a conveyor.

It is proposed to characterize the new integrating means by primary means including a movable member for sending out variable impulses, primary means including a movable member for transmitting motion, an integrator disc engageable with said second-named movable member to be driven thereby, means for engaging said disc and second movable member controlled by said impulses, a counter connected to and driven by said integrator disc, a source of constant speed rotations for driving one of said members, proportional means working in proportion to one of said variables for controlling one of said primary means, and proportional means working in proportion to the other of said variables for controlling the other of said primary means.

The primary means referred to in the previous paragraph were labeled "primary" means for the purpose of distinguishing them from the other means in said paragraph. The variable impulses referred to above may be of several types. Each type may be embodied in another modified form of this invention. For example, the variable impulses may be of constant frequencies but of variable lengths, or they may be of variable frequencies and of constant lengths. Two forms of the invention are disclosed in this specification covering these two types of impulses. The invention contemplates using cams as the movable members for controlling the impulses, but other adequate means might be used for the generation of above mentioned impulses.

The movable member in the primary means for transmitting motion referred to above, in each form of the invention, comprises a rotative table. In one form of the invention the source of constant speed rotation drives this table at a constant speed. In the other form of the invention the source of constant speed rotations drives the movable member which controls the impulses, in which case the impulses are of constant frequency.

Each form of the invention makes use of an integrator disc engageable with the rotative table to be driven thereby. It is a feature of this invention that the integrator disc intermittently engages the driven rotative table and that the

counter for registering the result of the integrated variables is directly driven by the integrator disc. By "directly driven" I mean that there is no need for a differential or other indirect mechanism. I may use a gear train which I consider as comprising one type of direct drive.

In the event that the integrating means is used to totalize continuously the weight of materials carried by a conveyor, the proportional means previously referred to working in proportion to one of said variables for controlling one of said primary means includes a scale beam of the pendulum type. The deflection of the scale beam will be in proportion to the load on the weigh section of the conveyor. This deflection may be used to control the impulses, as will be more fully understood from one form of this invention, or this deflection may be used to control the mechanical transmission of motion, as will appear from the other form of the invention disclosed.

When the integrating means is used to totalize continuously the weight of material carried by a conveyor; the speed of the conveyor is the other variable. In effect, the integrating means is continuously integrating a variable load traveling at a variable speed. The speed of the conveyor may be used to proportionally control the impulses, which way is used in one of the disclosed forms of the invention, or to proportionally control the transmission of motion (making use of the table previously mentioned) which way is used in the other form of the invention disclosed. The integrating means working under these conditions will integrate the product of speed $\times$ load (ft./min. $\times$ lbs./ft.).

Another object of this invention resides in the provision of simple means by which the integrating means may be calibrated. In one form of the invention it is proposed to control the lengths of the impulses for calibrating the integrating means. In the other form of the invention it is proposed to control the transmission of motion for calibrating the integrating means.

The invention also contemplates the provision of means for introducing lag in one of said proportional means or the other, to iron out large irregularities in one or the other of the two variables.

The invention further contemplates the use of electric impulses for the impulses referred to above. Furthermore, it is proposed that the means for engaging and disengaging the integrator disc with the rotative table be controlled by said electric impulses, preferably with the use of a solenoid and cooperative armature.

Still further the invention contemplates a novel construction of the elements of the integrating means and their mechanical relationship with each other. More specifically, it is proposed that the rotating table be located in a vertical plane and have a horizontal axle. It is proposed that the integrator disc be rotatively mounted on an integrator disc swing frame supported in a certain way with relation to said table.

Novel constructions are proposed for the impulse senders. Novel means is also proposed for moving said integrator disc swing frame away from the rotating table to move said integrator disc out of contact with the table between impulses.

Another object of the invention resides in constructing an integrating means of the type mentioned, which is relatively simple in construction and which may be manufactured and sold at a low cost.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a fragmentary schematic elevational view of a conveyor equipped with integrating means constructed in accordance with this invention.

Fig. 23 is a schematic wiring diagram of the second form of the invention.

The integrating means for continuously integrating two variables, such as a variable load traveling at a variable speed, in accordance with that form of the invention illustrated in Figs. 1 to 17 inclusive, is shown applied to a conveyor

25 having a conveyor belt 26 for carrying a variable load, which conveyor belt may travel at a variable speed. The conveyor belt 26 has a weigh section 27 which includes idler rollers 28 mounted upon a frame 29 which is supported at one end with a fulcrum 175 and which has its

20 other end supported by a suspension rod 176. This rod 176 is connected between the ends of a lever 177 which is pivotally supported at one end by the support means 178 and which has its other end connected with a rod 179 which is connected with one end of the scale beam 30 which is provided with the pendulum 31.

The conveyor belt 26 is supported by additional rollers 28' which are located outside of the conveyor weigh section 27. An adjustable

35 link 32 with universal joints 180 at its ends connects the pendulum 31 with a swivel arm 33 of a mechanical relay of the integrator, as will hereinafter be more fully described. The integrator includes a frame 35 having side walls 36, a front

40 wall 37, and a base wall 38. A mounting plate 39 is supported upon the frame 35 by lugs and fastening elements 39'. This mounting plate 39 rotatively supports a disc-like table 40 and a drive system for rotating this table. The table 40 is

45 in the nature of a vertical disc located to the front of the front wall 37 and mounted upon a horizontal shaft 41 which is rotatively supported by ball bearings 42 upon a tubular member 43 mounted on the mounting plate 39.

50 The shaft 41 is provided with a gear 44 back of the front wall 37 and meshing with a pinion 45 on a countershaft 46 rotatively supported by ball bearings 47 mounted on the tubular member 43, which is also mounted on and through the mounting plate 39. The shaft 46 is also provided with a gear 49 in front of the front wall

55 37 which in turn meshes with a pinion 50 mounted on the shaft of a self-starting synchronous induction motor 51 which is also mounted on the mounting plate 39. The construction is such that the synchronous induction motor 51, when operating, will drive the table 40 at a constant speed.

60 A mechanical relay is mounted on the top portion of the frame 35. This relay includes a relay carriage 52 provided with a pair of spaced grooved rollers 53 mounted on a track 54 fixedly mounted on the top portion of the front wall 37 of the integrator frame 35. The back portion of the

65 relay carriage 52 is formed with a vertical tubular portion 55 equipped with ball bearings 56 supporting a vertical swivel shaft 57 on the bottom end of which the said swivel arm 33 is mounted. This swivel arm 33 has a front hollow portion 58 in which a disc 59 is rotatively supported by

the ball bearings 60 mounted on the shaft 61, in turn mounted across the side walls of the hollow front portion 58. The grooved rollers 53 are rotatively mounted by ball bearings 62 upon a pair of spaced fixedly mounted studs 63 projecting from the front of the relay carriage 52. A front bar 64 is mounted across the front ends of the studs 63.

A horizontal stud 65 projects from the said front bar 64 and swivels supports a block 66. An integrator disc swing frame 67 is provided with a top pair of pivot studs 68 engaging the opposite sides of the block 66. The integrator disc swing frame 67 extends vertically and across the front of the table 40. The studs 68 serve to pivotally support the integrator disc swing frame 67 so that it may pivot towards and away from the table 40. Since the block 66 is turnably mounted on the stud 65, the swing frame 67 may also swing in a plane parallel to the table 40.

The disc 59 of the mechanical relay rests upon a mechanical relay rubber covered drum 69 which is rotatively supported between said side walls 36 of the frame 35. The drum 69 is connected up with a motor 70 of the geared head shaded pole type. This motor is supported on a mounting plate 71 supported by the arms 72 on a bracket 73 mounted on the outer side of one of the walls 36. The shaft of the motor 70 is provided with a pinion 74 which meshes with a gear 75 rotatively mounted on the mounting plate 71 and provided with a pinion 76 meshing with a gear 77 mounted on a shaft 78 connected with one end of the drum 69. The construction is such that the motor 70 drives the rubber covered drum 69, which in turn drives the disc 59, which I will hereafter refer to as a "swivel disc" because it is indirectly mounted on the swivel shaft 57 and swivels when the arm 33 is moved.

An integrator disc 79 is rotatively mounted on said integrator disc swing frame 67 and normally has a point on its periphery adjacent a "zero" or starting point on the table 40. As illustrated on the drawings this "zero" or starting point coincides with the axis of rotation of the table 40. The integrator disc 79 has a hub portion 80 rotatively mounted by ball bearings 81 upon a shaft 82 fixedly mounted across the sides of the swing frame 67. The integrator disc 79 is also provided with a hard rubber tire portion 83 which is held in position by a collar 84 fixedly mounted on the hub 80 with a set screw 85. The tire portion 83 is adapted to engage the table 40 for receiving rotations therefrom.

A counter 88 is connected to and is driven by the rotations of the integrator disc 79. More particularly, a counter drive gear 86 is fixedly connected with the hub 80 and meshes with a gear 87 mounted on the shaft of said master totalizing counter 88 which is fixedly mounted on the swing frame 67. The gear 87 is provided with a vernier hub 89 preferably graduated into 100 divisions for cooperation with the counter 88 by which it is possible to accurately read fractions indicated by the counter 88.

An adjustable counterweight 90 is mounted on the top of the swing frame 67 by which the swing frame and the various parts mounted thereon may be delicately balanced. This adjustable counterbalance weight 90 is threadedly engaged on a screw 91 mounted on the top of the swing frame 67. Normally, the swing frame 67 assumes a position in which the integrator disc 79 is out of contact with the table 40. It is resiliently urged and held in this position by a

hinge arm 92 which is pivotally mounted on a rod 93 mounted across the sides of the swing frame 67. The hinged arm 92 has a pair of downwardly directed fingers 94 positioned to the sides of the swing frame 67. Horizontal rods 95 are mounted on the bottom ends of the fingers 94 and extend towards a stationary plate 96 mounted across the front of the front wall 37 of the integrator plate 35 by the lug and fastening elements 96'. The free ends of each of the rods 95 support small steel balls 97 which normally rest against the plate 96. The plate 96 is in the nature of a stationary solenoid armature and is cooperative with a solenoid 98 supported on the swing frame 67.

The solenoid 98 is clamped by a pair of side bars 99 held on the frame 67 by the bolts 100. A bar 101 (see Figs. 4, 8 and 13) is mounted across the sides of the swing frame 67 and supports a projecting stud 102 which passes through an opening 103 in the hinged arm 92. This stud 102 has several nuts 104 threadedly mounted on its outer end. A spring 105 acts between the hinged arm 92 and the washer 106 mounted on the stud 102 and engaging against the innermost nut 104. This spring 105 acts to normally urge the swing frame 67 slightly forwards so that the integrator disc 79 is out of contact with the table 40. When the solenoid 98 is energized it moves towards the stationary core 96 correspondingly moving the swing frame 67 for engaging the integrator disc 79 against the table 40.

The integrating means also includes proportional frequency impulse means for producing impulses numerically in proportion to the speed of the conveyor belt 26 and said impulses being of constant lengths. This means includes a casing 107 stationarily supported in relation with the conveyor 25 and provided with a removable front cover 108. This cover is releasably held in position with several swing studs 109 provided with wing nuts 110. A gasket 111 is mounted around the edge of the casing 107 and is held in position on the edge portion of the casing by a stationary strip 112.

Within the casing 107 there is a mounting plate 113 mounted on the back wall of the casing. One of the rollers of the conveyor 25 or a conveyor pulley 131 is provided with a sprocket 114 engaged by an endless chain 115 engaging over a sprocket 116 mounted on a shaft 117 rotatively mounted within a bushing 118 extended through the back wall of the casing 107 and mounted on the mounting plate 113. The inner end of the shaft 117 is provided with a gear 119 which meshes with a gear 120 rotatively mounted on the mounting plate 113. This gear 120 is provided with a cam 121 having a single cam projection 122. This cam projection 122 is adapted to engage against the roller 123 of a switch arm 124 of a normally open micro-switch 125. This micro-switch 125 is mounted on a bracket which is adjustably clamped on a stud 127 mounted on the mounting plate 113. When the cam 121 rotates the projection 122 will strike the roller 123, depressing the lever 124 and closing the micro-switch. It is pointed out that the speed of rotation of the cam 121 will be in proportion to the speed of the conveyor belt 26, and consequently the micro-switch 125 will be operated in proportion to the speed of the conveyor belt 26.

Attention is now directed to the schematic electric wiring diagram of the device illustrated in Fig. 17. The supply circuit is indicated by the reference letters L1 and L2. The micro-switch

125 is connected in circuit 133 connected in parallel with the supply circuit and controls a normally closed inertia relay 130. This relay has a coil 131 which when energized opens the switch portion 132 with a slight delay. The switch portion 132 is connected in series in said circuit 133 which includes and controls an adjustable time delay relay 134. This adjustable time delay relay is of the type in which the contacts close instantly and open with delay, depending upon the adjustment thereof. The coil 131 of the relay 130 is in a circuit 135 shunting the relay switch 132. The time delay relay 134 controls circuit 136 connected in parallel with the supply circuit L1, L2. This circuit 136 includes in series the said solenoid 88. It also includes in series a normally closed limit switch 137. This limit switch 137 is operated by the mechanical relay of the integrating means. It is mounted on the track 54 (see Figs. 2 and 3). When the carriage 52 is in its starting position, corresponding with no load on the conveyor weigh section 27, one of the grooved wheels 53 engages the normally closed limit switch 137 holding it open. A manually operable switch 138 is connected in a circuit which shunts the normally closed limit switch 137 and is for the purpose of regulating the integrator, for the balance or no-load position, as will be hereafter more fully described. The schematic wiring diagram also discloses the circuits 139 and 140 in parallel with the supply circuit L1, L2 for the self starting synchronous induction motor 51, and the motor 70 of the mechanical relay.

The relay 134 is a standard commercial relay of the type in which the contacts instantly close and open with delay for a time interval selected according to the adjustment of the relay. For example, we may use the relay disclosed in U. S. patent to C. L. Anderson No. 2,175,865, granted October 10, 1939 and issued to Eagle Signal Corp. of Moline, Illinois, assignee.

The operation of this form of the invention is as follows:

The conveyor belt 26 is a section of an endless conveyor and continuously works, carrying a load of articles or material. When these articles or material pass the conveyor weigh section 27 the pendulum 31 of the pendulum type beam 30 will be deflected in direct proportion to the weight on the weigh section 27. The pendulum 31 will transmit the motion via the adjustable link 32 to the swivel disc arm 33 of the mechanical relay. This mechanical relay may be recognized by noting its pertinent parts which, besides the swivel disc arm 33, includes the electric motor driven rubber covered drum 69 upon which the disc 59 of the swivel disc arm 33 rests. The mechanical relay also includes the carriage 52 guided by wheels 53 on the track 54 and indirectly supporting the stud 95.

Normally, the carriage 52 is in a starting position, as illustrated in Figs. 2 and 3, in which one of the wheels 53 of the carriage 52 engages against the limit switch 137. When the parts are in this condition the swivel disc arm 33 is projecting rearwards at right angles to the axis of the rubber covered drum 69. At this moment the weight upon the conveyor weigh section 27 is zero. When some weight comes along and reaches and is carried across the weigh section 27 the beam 30 will be deflected and will indirectly cause the swivel disc arm 33 to be swiveled on the swivel shaft 57. This tilts the disc 59 in proportion to the amount that the swivel disc arm 33 is moved. When the disc 59 is tilted at an angle to the axis

of the rubber covered drum 69, the rubber covered drum 69 will drive the wheel 59 along its length until it reaches a new position in which it and the swivel disc arm 33 are again at right angles to the axis of the rubber covered drum 69. The lateral motion of the wheel 59 correspondingly moves the carriage 52. This mechanism is referred to as a mechanical relay because it follows the proportional motion of the pendulum 31 of the beam 30 and does this smoothly, ironing out any sudden changes of the load on the weigh section 27.

When the carriage 52 was at its starting position the integrator disc 79 was located at its "zero" or starting position, which in accordance with Fig. 3, corresponds with the axis of the table 40. When the integrator disc 79 is at this "zero" position it does not contact with the table 40 because the limit switch 137 is open. This breaks the circuit 136 through the solenoid 88 and therefore the spring 105 holds the integrator disc swivel frame 67 forwards so that the integrator disc 79 is out of contact with the table 40. However, as soon as the carriage 52 moves away from its "zero" position it carries along the integrator disc swing frame 67 so that the integrator disc 79 is now moving radially away from the center of the table 40. The table 40 is being rotated at a constant speed by the synchronous induction motor 51. It is pointed out that should the integrator disc 79 now be engaged against the table 40, the table 40 will impart rotations to the disc 79 which will transmit these rotations to the master totalizing counter 33. The mechanism just described for moving the carriage 52 from its zero position, essentially comprises proportional deflection means for moving the integrator disc swing frame 67 in a direction to move the integrator disc 79 radially of the center of rotation of the table 40 in proportion to the load variable on the conveyor weigh section 27.

The integrating means for continuously integrating a variable load traveling at a variable speed, or integrating two other types of variables, includes proportional frequency impulse means for producing impulses numerically in proportion to the speed variable, said impulses being of constant lengths, for moving the disc frame 67 in a direction to move said integrator disc 79 against said table 40 for and during each impulse. This proportional frequency impulse means may be traced from the pulley 181 of the conveyor 26. Rotations from this pulley 181 are indirectly transmitted to drive the cam 121 by the chain 115. This cam 121 will be rotated in direct proportion to the speed of the conveyor belt 26. Each rotation of the cam 121 will cause the projection 122 to move the lever 124 normally closing the normally open micro-impulse sender switch 125. Each time the switch 125 is closed the coil 131 of the normally closed inertia relay 130 will become energized so that the switch 132 of the relay opens. However, this switch 132 opens with slight delay. During this delay period the circuit 133 to the adjustable time relay 134 is closed. When switch 125 opens, the contacts of relay 130 close again, but the circuit 133 remains open because switch 125 is now open. If cam 121 should stop with switch 125 closed, relay 130 stays energized, its contacts remain open, and circuit 133 remains open.

The relay 134 is a standard commercial relay which may be purchased on the market and is of the type in which the contacts instantly close and open with delay, according to the ad-

justment of the relay. This delay may be anywhere from a fraction of a second, upwards. The purpose of having the relay 134 adjustable is to make it possible to calibrate the integrator. The impulses released by the relay 134 will control the circuit 136 which includes the solenoid 98. For each impulse, the solenoid 98 becomes energized and will be attracted to the solenoid armature 96, causing the integrator disc swing frame 67 to move towards the table 40 so that the integrator disc 79 engages the table 40 and receives rotative motion therefrom. As soon as the impulse ceases, the spring 105 will immediately move the swing frame 67 to disengage the integrator disc 79 from the table 40.

It should now be recognized that the integrating means is continuously integrating a variable load traveling at a variable speed. The variable load indirectly causes the integrator disc swing frame 67 to assume various positions in which the integrator disc 79 is in various radial positions from the axis of rotation of the table 40, these positions being proportional to the pendulum deflections. The table imparts therefore, upon contact with the integrator disc 79, rotative motion to the latter, also in proportion to the pendulum deflection. Simultaneously, the proportional frequency impulse means operating indirectly through the medium of the pulley 181 driving the cam 121 of the impulse sender, operates the solenoid 98 which causes the integrator disc swing frame 67 to engage the integrator disc 79 against the table 40 for each impulse. In this way the integrator disc 79 is integrating the two variables, which are totaled by the counter 88.

In Figs. 18-23 inclusive another form of integrating means is disclosed which operates on substantially the identical principle. In this form of the invention there is a conveyor 25 which may work at a variable speed and which carries a variable load past the conveyor weigh section 27. This conveyor weigh section 27 is provided with a beam type weighing device which includes the pendulum 31 connected with an adjustable link 32 operating the swivel disc arm 33 of a mechanical relay. This mechanical relay includes the carriage 52. It should be noted that up to this point the device is substantially identical in construction to the corresponding portion of the prior device. For this reason further details thereof will not be given, but identical parts have been indicated by like reference numerals.

The modified form of the invention now distinguishes from the prior form in the fact that a normally open micro-switch 150 is indirectly mounted on the carriage 52, see Fig. 21. More particularly, it is mounted on the bar 64 of the carriage 52. This switch 150 has an operator arm 151 provided with a roller 152 which rests on a movable member 153. This movable member 153 is in the nature of a cylinder. It is rotatively axially supported by the bearings 154. The cylinder 153 is provided with a triangular shaped cam 155 which has an apex portion at one end of the cylinder 153 and has its sides gradually diverging from this apex portion. The cam 155 is in the nature of a raised portion on one side of the cylinder 153. The cylinder 153 is connected up with a transmission 156 driven by a self-starting synchronous induction motor 51.

It should be recognized that up to this point we have described a proportional means working in proportion to one of said variables, namely, the load variable, which controls an impulse sender. As illustrated in Fig. 21, the carriage 52

of the mechanical relay is at its "zero" or starting position. Similarly, the wheel 152 of the normally open micro-switch impulse sender 150 is just adjacent the apex of the cam 155 so that the switch is open and no impulses are being sent, even though the cylinder 153 is rotating continuously at a constant speed. However, when a load passes the conveyor weigh section 27, the mechanical relay will be operated and will indirectly cause the carriage 52 to move away from the "zero" or starting position in proportion to the load on the weigh section 27. When the carriage 52 moves as stated, it carries along the switch 150 with its operator arm 151 and roller 152. Now the operator arm 151 will be raised for each rotation of the cylinder 153, and the length of time that the arm is raised will depend upon its position along the cam 155. It should be noted that we are now capable of sending constant frequency impulses of variable lengths in proportion to the load variable.

The normally open micro-switch impulse sender 150 is arranged in a parallel circuit (see Fig. 23) in the supply circuit L1, L2 which includes the solenoid 98 in series. The solenoid 98 is mounted upon an integrator disc swing frame 67'. This integrator disc swing frame 67' is pivotally supported at its top and freely depends. It is pivotally supported by the studs 68 which engage opposite sides of a block 158. This block 158 is slidably mounted upon the frame 38' of the integrator. A rotatively mounted screw 159 threadedly engages the block 158. This screw is provided with a knob 160. The integrator disc swing frame 67' supports the integrator disc 79 which is indirectly connected with the master totalizing counter 88 mounted on the frame 67'. The integrator disc 79 is immediately adjacent the table 40 which is disposed in a vertical position and fixed upon a horizontal shaft 41. This horizontal shaft 41 is rotatively supported on the frame 38'. It is provided with a sprocket 162 which is engaged by a chain 115 connected with the pulley 181 of the conveyor 25.

In other respects this form of the invention is identical to the previous form and like parts have been indicated by like reference numerals.

It should be noted that the table 40 will be driven in direct proportion to the speed of the conveyor belt 26 of conveyor 25. This constitutes one of the variables. As already pointed out, the other variable, that is, the load, controls the impulses which are of constant frequency but of variable lengths.

The operation of this form of the invention is as follows:

The load variable, that is, the load passing the conveyor weigh section 27 will operate the mechanical relay to indirectly move the carriage 52 of the relay for indirectly moving the normally open micro-switch 150 along the cam 155 for sending out impulses in proportion to the load. These impulses will operate the solenoid 98 which will be attracted to the armature 96 and will cause the integrator disc 79 to engage the rotating table 40. The engagement of the integrator disc 79 with the table 40 will be in direct proportion to the load variable. The table 40 is rotating at a variable speed as it is directly driven by the conveyor 25. Consequently, the master totalizing counter 88 is totaling the two variables.

The integrating means may be calibrated by turning the screw 160 so as to adjust the position of the integrator disc frame 67' for adjusting the

radial position of the integrator disc 79 with relation to the axis of rotation of the table 40. Once this adjustment has been properly made it is not necessary to disturb it.

In order to better understand the invention certain similarities between the two disclosed forms thereof will now be pointed out. It should be noted that both integrating means are continuously integrating two variables. Each integrating means has primary means which includes a movable member for sending out variable impulses. The movable member in the first disclosed form of the invention is the rotative cam 121. The movable member in the second disclosed form of the invention is the rotating cam 155. In the first form of the invention the frequencies of the impulses are variable because the cam 121 is driven by the variable speed conveyor 25. However, the impulses are of identical lengths because of the time delay relay 134. In the second form of the invention the impulses are of constant frequency, but of variable lengths because of the varying character of the cam 155. This means was labeled "primary" so that it may be distinguished from subsequent means hereafter referred to.

Both integrating means have another primary means which includes a movable member for transmitting motion. This movable member is the table 40, in each of the forms of the invention. This movable member 40 transmits motion to the integrator disc 79. This means is also labeled "primary" merely to distinguish it from means hereafter referred to. Each of the two forms of integrating means has an integrator disc 79 which is engageable with the second-named movable member, that is, the rotative table 40, to be driven thereby. Each of the two forms of integrating means have means for engaging and disengaging said integrator disc 79 and said second movable member (table 40) and this means is controlled by said impulses. It should be noted that in each form of the invention the impulses are sent to the solenoid 93 which indirectly moves the integrator disc frame to engage or disengage the integrator disc 79 from the table 40. Each form of the invention is provided with a totalizing counter 83 connected to and driven by the integrator disc 79. Each form of the invention has a source of constant speed rotations. In the first form of the invention it is the synchronous induction motor 61 indirectly driving the table 40 at a constant speed. In the second form of the invention it is the synchronous induction motor 51 driving the cam 155 at a constant speed.

Each form of the invention also has proportional means working in proportion to one of the variables for controlling one of said primary means just mentioned above. Each integrator also is provided with proportional means working in proportion to the other of said variables for controlling the other of said primary means. It is believed that this will be obvious from the previous portions of this specification.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. Integrating means for continuously integrating a variable load traveling at a variable speed, comprising a constant speed rotating table, a disc frame extending across said table, an integrator disc rotatively mounted on said disc frame and normally having a point on its periphery adjacent a "zero" or starting point on said table, a counter connected to and driven by rotations of said disc, proportional deflection means for moving said disc frame in a direction to move said integrator disc radially of the center of rotation of said table in proportion to said load variable, proportional frequency constant length impulse means for producing impulses of constant length numerically in proportion to said speed variable for moving said disc frame in a direction to move said integrator disc against said table for and during each impulse, and means for moving said disc frame in a direction to move said integrator disc out of contact with said table between said impulses.

2. Integrating means for continuously integrating a variable load traveling at a variable speed, comprising a constant speed rotating table, a disc frame extending across said table, an integrator disc rotatively mounted on said disc frame and normally having a point on its periphery adjacent a "zero" or starting point on said table, a counter connected to and driven by rotations of said disc, proportional deflection means for moving said disc frame in a direction to move said integrator disc radially of the center of rotation of said table in proportion to said load variable, proportional frequency constant length means for producing impulses of constant length numerically in proportion to said speed variable for moving said disc frame in a direction to move said integrator disc against said table for and during each impulse, means for moving said disc frame in a direction to move said integrator disc out of contact with said table between said impulses, and means for interrupting and discontinuing the sending of said impulses when said integrator disc is at said "zero" position.

3. Integrating means for continuously integrating a variable load traveling at a variable speed, comprising a constant speed rotating table, a disc frame extending across said table, an integrator disc rotatively mounted on said disc frame and normally having a point on its periphery adjacent a "zero" or starting point on said table, a counter connected to and driven by rotations of said disc, proportional deflection means for moving said disc frame in a direction to move said integrator disc radially of the center of rotation of said table in proportion to said load variable, proportional frequency constant length impulse means for producing impulses of constant length numerically in proportion to said speed variable for moving said disc frame in a direction to move said integrator disc against said table for and during each impulse, means for moving said disc frame in a direction to move said integrator disc out of contact with said table between said impulses, and means for adjusting the length of the impulses sent out by said constant length impulse means for the calibration of said integrating means.

4. Integrating means for continuously integrating a variable load traveling at a variable speed, comprising a frame, a vertical table having a horizontal shaft rotatively mounted on said frame, means for rotating said shaft at a constant speed, a carriage horizontally slidably

mounted on said frame and above said table to move across said table, an integrator disc swing frame swingingly and pivotally depending from said carriage to move across said table and towards and away from said table, an integration disc rotatively mounted on said frame and normally having a point on its periphery adjacent a "zero" or starting point on said table, a counter connected to and driven by the rotations of said disc, proportional deflection means for moving said carriage across said table for moving said disc swing frame in a direction to move said integrator disc radially of the center of rotation of said table in proportion to said load variable, proportional frequency constant length impulse means for producing constant length impulses numerically in proportion to said speed variable for moving said disc swing frame towards said table for and during each impulse, and means for moving said disc frame away from said table to move said integrator disc out of contact with said table between said impulses.

5. Integrating means for continuously integrating a variable load traveling at a variable speed, comprising a frame, a vertical table having a horizontal shaft rotatively mounted on said frame, means for rotating said shaft at a constant speed, a carriage horizontally slidably mounted on said frame and above said table to move across said table, an integrator disc swing frame swingingly and pivotally depending from said carriage to move across said table and towards and away from said table, an integration disc rotatively mounted on said frame and normally having a point on its periphery adjacent a "zero" or starting point on said table, a counter connected to and driven by the rotations of said disc, proportional deflection means for moving said carriage across said table for moving said disc swing frame in a direction to move said integrator disc radially of the center of rotation of said table in proportion to said load variable, proportional frequency constant length impulse means for producing constant length impulses numerically in proportion to said speed variable for moving said disc swing frame towards said table to move said integrator disc against said table for and during each impulse, and means for moving said disc frame away from said table to move said integrator disc out of contact with said table between said impulses, said impulse means including a solenoid mounted on said swing frame and cooperative with a solenoid armature mounted on said first named frame.

6. Integrating means for continuously integrating a variable load traveling at a variable speed, comprising a frame, a vertical table having a horizontal shaft rotatively mounted on said frame, means for rotating said shaft at a constant speed, a carriage horizontally slidably mounted on said frame and above said table to move across said table, an integrator disc swing frame swingingly and pivotally depending from said carriage to move across said table and towards and away from said table, an integration disc rotatively mounted on said frame and normally having a point on its periphery adjacent a "zero" or starting point on said table, a counter connected to

and driven by the rotations of said disc, proportional deflection means for moving said carriage across said table for moving said disc swing frame in a direction to move said integrator disc radially of the center of rotation of said table in proportion to said load variable, proportional frequency constant length impulse means for producing constant length impulses numerically in proportion to said speed variable for moving said disc swing frame towards said table to move said integrator disc against said table for and during each impulse, and means for moving said disc frame away from said table to move said integrator disc out of contact with said table between said impulses, said impulse means including a solenoid mounted on said swing frame and cooperative with a solenoid armature mounted on said first named frame, and a normally open switch impulse sender controlling a normally closed inertia relay of the type which when energized will have its contacts open with slight delay, and said relay controlling an adjustable time delay relay of the type in which the contacts close instantly and open with delay, and said delay relay controlling electric impulses to said solenoid.

7. Integrating means for continuously integrating a variable load traveling at a variable speed, comprising a frame, a vertical table having a horizontal shaft rotatively mounted on said frame, means for rotating said shaft at a constant speed, a carriage horizontally slidably mounted on said frame and above said table to move across said table, an integrator disc swing frame swingingly and pivotally depending from said carriage to move across said table and towards and away from said table, an integration disc rotatively mounted on said frame and normally having a point on its periphery adjacent a "zero" or starting point on said table, a counter connected to and driven by the rotations of said disc, proportional deflection means for moving said carriage across said table for moving said disc swing frame in a direction to move said integrator disc radially of the center of rotation of said table in proportion to said load variable, proportional frequency constant length impulse means for producing constant length impulses numerically in proportion to said speed variable for moving said disc swing frame towards said table to move said integrator disc against said table for and during each impulse, and means for moving said disc frame away from said table to move said integrator disc out of contact with said table between said impulses, said impulse means including a solenoid mounted on said swing frame and cooperative with a solenoid armature mounted on said first named frame, and a normally open switch impulse sender controlling a normally closed inertia relay of the type which when energized will have its contacts open with slight delay, and said relay controlling an adjustable time delay relay of the type in which the contacts close instantly and open with delay, and said delay relay controlling electric impulses to said solenoid, and a normally closed limit switch for breaking the circuit to said solenoid when said integrator disc is at the "zero" position on said table.

JOHN LOUIS CHRISTMANN.
